DESIGN FOR A BADGE OR OTHER SIMILAR ARTICLE

Matthew R. Korshin, New York, N. Y.

Application July 26, 1941, Serial No. 102,500

Term of patent 3½ years

To all whom it may concern:

Be it known that I, Matthew R. Korshin, a citizen of the United States residing in the city, county, and State of New York, have invented a new, original, and ornamental Design for a Badge or other Similar Article, of which the following is a specification, reference being had to the accompanying drawing, forming a part thereof.

In the drawing—

Figure 1 is a front elevation of the badge or other similar article showing my new design; and

I claim:

The ornamental design for a badge or other similar article, as shown.

MATTHEW R. KORSHIN.
